UNITED STATES PATENT OFFICE.

CHARLES BERTHELOT, OF PARIS, FRANCE.

OVEN WITH REGENERATOR.

1,361,671.

Specification of Letters Patent.

Patented Dec. 7, 1920.

Application filed August 15, 1919. Serial No. 317,779.

To all whom it may concern:

Be it known that I, CHARLES BERTHELOT, a citizen of the Republic of France, and residing at Paris Seine Department, No. 94 Rue Saint-Lazare, in the Republic of France, engineer, have invented certain new and useful Improvements in Ovens with Regenerators. (Case A,) of which the following is a specification.

10 The invention relates to an oven with vertical flues or heating chambers and regenerators more particularly adapted to the manufacture of metallurgical coke and illuminating gas. It is suitable for the carbonization of coal and other materials.

15 Reference is made to my co-pending application No. 317780, ovens and regulators.

20 The oven may be designated an oven with longitudinal regenerators in parallel. The regenerator, which extends under the oven, is divided into compartments, generally 25 four, completely separated from each other by transverse partitions. This arrangement affords the advantage of preventing short circuits and stagnant zones in the passages, which are of course not favorable to the heating efficiency of the regenerator. Moreover, the parallel arrangement has the considerable advantage of involving only a very 30 slight loss of charge at the place of discharge of the burnt gases. Consequently, the difference of pressure between the heating chambers and the carbonizing chambers is reduced to a minimum, and this reduces 35 the risk of intermingling the gases in these two kinds of chambers, such intermingling being, as is known, injurious to the output of by-products and the quality of the gas produced.

40 Favorable to the thermal efficiency of the system, the arrangement is also advantageous to the stability of the structure, by reason of the transverse walls dividing the regenerators.

45 The arrangement also has the advantage that it allows of using a single collecting flue for the burnt gases. As compared with the usual arrangements, which generally comprise two flues used alternatively, this results in an evident simplification, and also 50 enables the single flue to be kept at a constant temperature. This insures uniform draft through the chimney, and consequently the most favorable combustion of 55 the gas for heating the battery of ovens, and greatly facilitates the control and regula-

tion of the combustion. It may be remarked that the possibility of using a single collecting flue for the burnt gases allows of reducing from five to one the number of regulating dampers for the collecting flues. However, the invention does not exclude the use of two flues operating simultaneously. Finally, another advantage of the longitudinal regenerators in parallel is that each compartment of the regenerator receives the burnt gases of a well defined zone of the heating chamber, which is divided into compartments in the same way. This facilitates regulation by proportioning the volume of air for combustion to the volume of combustible gas, with the result of uniform heating of the wall of the furnace. Hitherto, with all the burnt gases uniting in one regenerator, the regulation and control of the combustion were both inconvenient and irregular.

The invention is illustrated in the accompanying drawing, in which:—

Figure 1 is a longitudinal section of oven, 80 with flues and regenerators, the left hand part being a section on the line A—A of Fig. 2, and the right hand part a section on the line B—B of Fig. 2.

Figs. 2 and 3 are horizontal sections, the former on the line C—C of Fig. 1, at the level of the air and gas inlet conduit to the combustion chambers, and the latter on the line D—D, at the base of the regenerator.

Fig. 4 is a vertical section, the left-hand part on the line E—E of Figs. 2 and 3, and the right-hand part on the line F—F.

The circulation of the gases in this oven is as follows:—

The heating gas is supplied through the pipes 1 and 1¹. For the first half hour it is distributed to the heating chambers through the valves 2 and 2¹, and for the second half hour through the valves 3 and 3¹. A series of conduits distributes the gas to a series of calibrated orifices or twyers 18 opening into the vertical heating chambers 5 and 7. During the first half hour, for example, in the first half on the left of the combustion chamber, the hot air coming from the compartment of the regenerator 8 corresponding to this half arrives through the orifices 4 and supports the combustion of the gas.

The twyers 18 are accessible from the upper part of the oven by means of movable plugs 20 and 19¹, to allow of regulating the admission of gas along the wall of the oven.

The regulation of the heat is also effected by adjusting the dampers 19.

The incandescent gases ascend in the heating chambers 5, traverse the horizontal conduit 6, and descend through the heating chambers 7 to the compartment 9 of the regenerator.

For the right hand half of the combustion chamber the flow of the gases is symmetrical 10 with that on the left.

During the second half hour the flow of the gases is reversed. The gases ascend in the heating chambers 7 and descend in the heating chambers 5, on their way to the regenerator compartment 8 or 11.

Under a single oven, the four compartments forming a regenerator are traversed simultaneously during one period by the air for combustion to be heated, and during the 20 following period by the burnt gases whose sensible heat is to be recovered. In this way, during a given period, generally half an hour, each of the regenerators of a given parallel is traversed by the air for combustion for the vertical heating chambers placed on both sides of the oven above this regenerator, and each of the regenerators of the other parallel is traversed by the burnt gases coming also from both sides of the oven 25 placed over the regenerator. In the following period the reverse takes place.

For each of the regenerator compartments, 8, 9, 10, 11, there is a conduit designated 12, 35 13, 14, and 15 respectively situated at its base and terminating in a cast iron T-union 16 having a cast iron register appertaining to each conduit. By means of this register the admission of air to each compartment of the regenerator and the combustion chamber 40 is regulated. The whole of the burnt gas is conducted by the union 16 past the damper 17 and through the pipe 21 to the flue 22 leading to the chimney.

It may be remarked that the combustion 45 chamber is longitudinally divided into four equal parts, those at the ends being traversed simultaneously by parallel incandescent streams of gas flowing in the same direction, but separate. It is thus possible to have the 50 period of direct heating, or in other words the period of heating by ascending currents of gas, longer than the period of heating the said end parts by descending currents of gases of combustion. The losses of heat by 55 radiation, inevitable at the doors of the ovens, are thus compensated. The duration of heating the two central parts is thus reduced, but this is no disadvantage, as they are located in the middle of the oven structure.

Claims:

1. An oven comprising carbonizing chambers, vertical flues, regenerators located below said chambers, longitudinal flues above 65 said vertical flues, conduits connecting said

regenerators to the lower part of the vertical flues adjacent thereto, conduits connecting the upper part of the vertical flues to the longitudinal flues above the same, means for placing in communication one half of the 70 vertical flues located between two carbonizing chambers with the regenerator under one of said chambers and with the longitudinal flue over said vertical flues, means for placing in communication the said longitudinal flue with the other half of said vertical flues, and the latter with the regenerator under the adjacent chamber.

2. An oven comprising carbonizing chambers, vertical flues, regenerators located below said chambers and divided into compartments in series, longitudinal flues above said vertical flues, conduits connecting said regenerators to the lower part of the vertical flues adjacent thereto, conduits connecting the upper part of the vertical flues to the longitudinal flues above the same, means for placing in communication one half of the 80 vertical flues located between two carbonizing chambers with the regenerator under one of said chambers and with the longitudinal flue over said vertical flues, means for placing in communication the said longitudinal flue with the other half of said vertical flues, and the latter with the regenerator under the adjacent chamber.

3. An oven comprising carbonizing chambers, vertical flues, regenerators located below said chambers, longitudinal flues above said vertical flues, conduits connecting said regenerators to the lower part of the vertical flues adjacent thereto, conduits connecting the upper part of the vertical flues to the longitudinal flues above the same, means for placing in communication one half of the 85 vertical flues located between two carbonizing chambers with the regenerator under one of said chambers and with the longitudinal flue over said vertical flues, means for placing in communication the said longitudinal flue with the other half of said vertical flues, and the latter with the regenerator under the adjacent chamber.

4. An oven comprising carbonizing chambers, vertical flues, regenerators below said chambers, longitudinal flues above said vertical flues, conduits connecting said regenerators to the lower part of the adjacent vertical flues, conduits connecting the upper part of the vertical flues to the longitudinal flues above the same, means for placing in communication one half of the 90 vertical flues located between two carbonizing chambers with the regenerator under one of said chambers and with the longitudinal flue over said vertical flues, means for placing in communication the said longitudinal flue with the other half of said vertical flues, and the latter with the regenerator under the adjacent chamber, a main located on one side of the oven, conduits connecting said main to the regenerators, for the discharge of the smoke gases from the latter.

5. An oven comprising carbonizing chambers, vertical flues, regenerators below said chambers, longitudinal flues above said vertical flues, conduits connecting said regenerators to the lower part of the adjacent vertical flues, conduits connecting the upper part of the vertical flues to the longitudinal flues above the same, means for placing in communication one half of the 95 vertical flues located between two carbonizing chambers with the regenerator located below one of said chambers and with the longitudinal flue above said vertical flues, means for placing in communication the said longitudinal flue with the other half of said vertical flues, and the latter with the regenerator under the adjacent chamber.

the other half of said vertical flues, and the latter with the regenerator under the adjacent chamber, means for circulating air in parallel and in the same direction in all the 5 regenerator compartments under each carbonizing chamber, means for then circulating said air through one half of the vertical flues on each side of each carbonizing chamber, means for circulating gases of combustion coming, as to one half from the first 10

mentioned flues, and as to the other half from the second mentioned flues, through the said regenerator compartments.

In testimony, that I claim the foregoing as my invention I have signed my name in 15 presence of two subscribing witnesses.

CHARLES BERTHELOT.
